UNITED STATES PATENT OFFICE

2,162,662

CAM-LAPPING MACHINE

Herbert S. Indge, Westboro, Mass., assignor to
Norton Company, Worcester, Mass., a corpora-
tion of Massachusetts

Application April 13, 1938, Serial No. 201,755

3 Claims. (Cl. 51—64)

The invention relates to abrading machines, and more particularly to a camshaft lapping machine.

One object of the invention is to provide a cam lapping machine which shall more effectively 5 polish the cams by producing a greater number of lapping lines in diverse directions. Another object of the invention is to provide a cam lapping device achieving additional contact with the work piece. Another object of the invention is to provide 10 a cam lapping device achieving a higher polish on the work piece. Other objects will be in part obvious or in part pointed out hereinafter.

The invention accordingly consists in the features of construction, combinations of elements, 15 and arrangements of parts, as will be exemplified in the structure to be hereinafter described, and the scope of the application of which will be indicated in the following claims.

In the accompanying drawing illustrating one 20 of many possible embodiments of the mechanical features of this invention, the single figure is a cross sectional view through a lapping arm and reciprocating slide of a machine according to U. S. Letters Patent No. 2,092,734, illustrating the 25 improved features.

The machine of the aforesaid patent comprises 30 a camshaft lapper for simultaneously lapping all the cams and also all the bearings of an automotive camshaft. All cams and bearings are simultaneously lapped in the machine by rotation 35 of the camshaft with individual cams in contact with abrasive paper or cloth which is rapidly reciprocated in the direction of the axis of the camshaft, and which is moved forward and back by a master camshaft corresponding to the product camshaft, whereby to maintain contact between the abrasive paper or cloth and the several 40 cams being lapped. The instrumentalities for lapping the bearings need not be modified according to the present invention and may be assumed to be the same as shown in the aforesaid patent.

Referring now to the single figure of the drawing, there are therein shown the two spaced bars 45 and 11 supporting the reciprocating slide 12. By means of cooperating dovetailed ways 13 and 14, the slide 12 adjustably mounts a plurality of lapping arms 15. The ways 13 are part of the slide 12 and the ways 14 are part of the several arms 15. The arms can thereby be located at the 50 desired spaced positions corresponding to the spacing of the individual cams 16 on the camshaft 17 to be lapped. When once the correct position of adjustment is found for each arm 15, a gib 18 is tightened by means of a screw 19 and this holds 55 the arm 15 firmly in place.

Each of the lapping arms 15 is provided with a longitudinally extending aperture 20 which is adapted to receive a slide 21. The slide 21 is supported on its lower surface by a pair of spaced rollers 22 and 23 which are rotatably supported on studs 24 and 25, respectively, this constituting an anti-friction support for the slide 21, which is movable towards and from the camshaft 17. In order to eliminate back-lash or lost motion there is provided an adjustable member 30 supporting a 10 pair of rollers 31 and 32, this adjustable member 30 being adjustable in a vertical direction by means of a screw 33 carried by a projection 34 of the lapping arm 15.

According to the aforesaid patent (issued on 15 application of myself and George E. Hulbert), a master camshaft 35 is rotated synchronously with the camshaft 17 being lapped. According to the aforesaid Patent 2,092,734, a contact is established 20 between a member carried by each slide 21 and the corresponding master cam 36. I provide, according to the present invention, a forked end 37 at the rear of the slide 21 and a strap 38 extending between the ends of the fork and around the master cam 36. This strap 38 is attached by 25 means of caps 39 and screws 40 to the fork 37 and it gives to the slide 21 a somewhat different motion than the device shown in the aforesaid patent. There is provided a spring 40 (as in the patent) 30 extending between a stud 41 attached to the slide 21 and a pin 42 attached to the lapping arm 15. The pin 42 extends between holes provided in the aperture 20 in the sides of the lapping arm 15, and additional holes 43 are provided for adjustment. It will be seen from the foregoing that the slide 21 35 is oscillated back and forth by the master cam 36.

At the front of each slide 21 I provide a band 45 of abrasive cloth, the abrasive side of which faces toward the front of the machine. This band 45 extends between the ends of a fork 46 formed at 40 the front of the slide 21, which fork is similar in shape to the fork 37. Caps 47 and screws 48 hold the abrasive cloth 45 in place.

There is provided also the supply reel 50 and the take-up or winding up reel 51, both supported 45 from the slide 21 and both of which may be identical with the corresponding reels shown in the aforesaid patent.

By means of a work supporting center and a driving member, as shown in the patent, the work 50 piece camshaft 17 is rotated. By means of suitable transmission mechanism as shown in the patent, the master camshaft 35 is rotated. The reciprocating slide 12 reciprocates as described in the patent. The abrasive paper, commonly re- 55

ferred to as sandpaper, 52, with its abrasive side outermost, is held in position by the band 45 of abrasive cloth against the cam 16. The fork 46 being substantially the same size as the fork 37 5 and the band 45 being substantially the same size as the band 38, and the master cam 36 being substantially the same size as the product cam 16, the motion imparted to the slide 21 is such as to keep the abrasive paper 52 in continuous contact 10 with product cam 16 by the pressure of the spring 40. The abrasive cloth 45 causes the abrasive paper to follow the reciprocations of the slide 21. There is thus produced a lapping action upon the product camshaft and the lapping covers a wide 15 area at a given instant. Thereby a much more effective lapping and polishing is achieved. When and as the sandpaper 52 is worn out, the operator, by the means clearly described in the patent, may take up a little on the take-up roll 51, the reel 50 20 automatically feeding out by an equal amount.

The bands 38 and 45 are virtually slings. Preferably some means is provided to prevent side motion of the slings and to this end I provide guard plates 55 and 56 for the bands 38 and 45, 25 respectively. There are a pair each of the guard plates 55 and 56, fastened by screws to the sides of the slides 21, as clearly indicated in the drawing. The width of the slides 21 should be greater than the width of the cams 16 and 36 plus the 30 amplitude of reciprocation and under such conditions the slings or bands are virtually prevented from sidewise motion.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as 10 illustrative and not in a limiting sense. 5

I claim:

1. In apparatus of the class described, a lapping arm, a slide carried by said lapping arm, forks at each end of said slide, slings carried by 15 the forks, a master cam engaged by one sling, and sheet abrasive carried by the other sling to engage a work piece to be lapped.
2. In apparatus of the class described, a slide, means to reciprocate the slide, a sling carried by 20 the slide, a sheet of abrasive material held by the sling whereby to lap a cam, and side guides to prevent side motion of the sling.
3. Lapping apparatus for lapping rotating bodies comprising a fork, a sling carried by the 25 fork, a supply reel of sheet abrasive, a take-up reel for sheet abrasive, the sheet of abrasive being held by the sling in contact with the rotatable part to be lapped, and side guides held by the fork to prevent side motion of the sling. 30

HERBERT S. INDGE.
